UNITED STATES PATENT OFFICE.

GEORGE F. MULHOLLAND, OF BELLEVILLE, ILLINOIS.

DESIGN FOR A BOTTLE FOR A FLOATING SIGNAL.

Application filed July 23, 1921. Serial No. 487,194. Term of patent 7 years.

To all whom it may concern:

Be it known that I, GEORGE F. MULHOLLAND, a citizen of the United States, residing at Belleville, in the county of St. Clair, State of Illinois, have invented a new, original, and ornamental Design for Bottles for Floating Signals, of which the following is a specification, reference being had to the accompanying drawing, forming part thereof.

The figure is a perspective view of a bottle for a floating signal showing my new design.

I claim:—

The ornamental design for a bottle for a floating signal as shown.

GEO. F. MULHOLLAND.

Witnesses:

W. F. KRICHER,
A. F. MILLER.
